UNITED STATES PATENT OFFICE.

WILLIAM HENRY HACKMANN, OF DIXON, CALIFORNIA.

OIL-BURNER.

1,132,471.

Specification of Letters Patent.

Patented Mar. 16, 1915.

Application filed December 2, 1914. Serial No. 875,113.

To all whom it may concern:

Be it known that I, WILLIAM H. HACKMANN, a citizen of the United States, and a resident of Dixon, county of Solano, State 5 of California, have invented a new and Improved Oil-Burner, of which the following is a full, clear, and exact description.

My invention, while applicable to crude oil burners for locomotives and steam engines generally, is more particularly designed for embodiment in the burners of traction engines pulling combination harvesters.

The danger from fire in the harvest field 15 is very great with ordinary types of burners, owing to the ejection of sparks due to the deposit of carbon in the smoke stack.

Objects of my invention are to provide a burner in the use of which carbon deposits 20 are prevented in the burner and smoke stack, thereby obviating the clogging of the burner and the danger from fire caused by sparks; to provide a burner of the gravity feed type employing a steam jet to produce a fuel mixture 25 in the form of a spray and insure a steady discharge of the fuel mixture without preheating of the crude oil to a high degree and the liability of the fuel column being forced back in the feed pipe; to provide 30 a burner that may be so arranged at the front of the furnace, as to direct a spray of fuel and steam upwardly to the fire box, thereby to effect a thorough mixing of the fuel and steam in the fire box; to provide 35 an oil burner free from the danger of back fire; to provide for the discharge of the fuel in a steady and equalized stream; and to provide a burner of simple construction, easily 40 adjusted and applied.

The special character of my improved burner and its distinctive features will appear from the specific description following.

Reference is had to the accompanying drawings forming part of this specification, 45 in which similar characters of reference indicate corresponding parts in all the views, and in which:

Figure 1 is a side elevation of my improved burner showing the same mounted 50 for use; Fig. 2 is a longitudinal vertical section of the burner on a large scale; Fig. 3 is a fragmentary view showing in perspective the nozzle of the burner body, or the shell; and Fig. 4 is a similar view of the steam 55 nozzle.

In constructing a practical embodiment

of my invention in accordance with the illustrated example, the body of the burner consists of an elongated shell 10 adapted to contain liquid fuel, and has suitable means at 60 its rear end for establishing connection with the fuel supply. In the illustrated form a head 11 has threaded connection with the shell 10 and with a vertical oil pipe 12 to be connected in practice with any elevated 65 source of supply. The oil pipe 12 is provided with a valve 13, preferably a globe valve, to control the fuel feed.

Within the fuel shell 10 is a longitudinally disposed steam tube 14 which extends 70 through the head 11 to a steam pipe 15 which communicates with the steam space of the boiler at any convenient point, as at 16. The steam pipe 15 is equipped with a controlling valve 17.

The shell 10 at its front end is formed into a nozzle, being flattened, and presenting a transverse, oblong discharge slot 18. The slot 18 is directly beneath the top of the shell 10, and below the said slot the shell 10 80 is formed with a front 19 extending obliquely upward from the bottom of the shell, the upper edge of the front wall 19 defining the bottom of the slot 18. The steam tube 14 is formed to correspond with 85 the nozzle and discharge slot of the fuel shell, being flattened as best seen in Fig. 4, and formed with a transverse oblong discharge slot 20 similar to the slot 18 of the fuel shell but smaller; also the front of the 90 steam tube 14 is formed with an oblique wall 21 corresponding in shape and direction to the front wall 19 of the fuel shell and substantially parallel with the latter.

The steam tube 14 is disposed in the shell 95 10 nearer the top thereof than the bottom, and the discharge slot 20 of the steam tube is thus located inward or rearward from the slot 18 of the fuel shell and below the latter. The arrangement provides for an ample 100 supply of fuel at the front of the burner between the walls 19 and 21 and immediately adjacent thereto with a body of oil maintained between the discharge slots of the steam nozzle and the fuel nozzle.

The invention is shown in connection with a boiler A of the locomotive type, and is disposed in an opening a at the front of the boiler leading to the fire box near the bottom. The form of the burner at the front 110 as described causes a steam spray to be directed obliquely upwardly and forwardly to

2
and through the discharge slot 18 of the fuel shell and through the intervening body of crude oil between the slots 18 and 20. The result is that a spray of combined steam and fuel is directed upwardly into and through the fire box, and the fuel and steam will thoroughly mix in the fire box, so that an ample supply of fuel is discharged in a steady and equalized spray. The burner is
5 free from deposits of carbon, and the composition is such that no carbon will be deposited in the smoke stack with the resulting liability of danger from sparks; also, no preheating of the fuel is required, and therefore
10 no back pressure is developed in the burner, with the liability of forcing back the fuel column in the gravity feed pipe.

Having thus described my invention, what I claim as new and desire to secure by Letters Patent, is:

- 20 1. A crude oil burner of the gravity feed type, comprising an outer elongated shell having means at its rear end for connection with a gravity fuel supply, and an elongated inner steam tube within said shell below the top of the latter and having a connection at its rear end for receiving a steam supply, the said steam tube gradually inclining upward from its rear to its front end, said shell
25 being formed at the front end with a flattened discharge nozzle presenting an oblong discharge slot transversely disposed directly adjacent to the top of the shell, the said nozzle, below the slot, presenting a front wall
30

inclining upwardly and forwardly from the bottom of the shell and in front of the steam tube and the said steam tube having a correspondingly formed flattened nozzle with an oblong discharge slot below and rearward of the slot of the fuel nozzle, the steam nozzle 40 having an upwardly inclined front wall spaced from and substantially parallel with the inclined front of the fuel nozzle.

2. A fuel burner of the character described, comprising an elongated outer fuel shell having a flattened discharge nozzle at the front end presenting a transverse oblong discharge slot directly adjacent to the flattened top of the shell, a head having threaded connection with the rear end of the shell and with a vertical oil supply pipe, and an elongated tube disposed longitudinally within the shell and extending at its rear end through the said head, said tube being provided with means at its rear end to connect with a fluid supply to be mixed with the fuel and having at its front end a nozzle presenting an oblong, transverse discharge slot in the rear of and below the discharge slot of the shell and adjacent to the top of 50 the said tube.

In testimony whereof I have signed my name to this specification in the presence of two subscribing witnesses.

WILLIAM HENRY HACKMANN.
